UNITED STATES PATENT OFFICE.

DORSEY F. ASBURY, OF BROOMES ISLAND, MARYLAND.

RADIO APPARATUS.

Application filed December 15, 1926. Serial No. 155,016.

My invention relates to radio apparatus and has particular reference to improvements in operating means for the movable parts of tuning units, such, for example, as 5 variable plate condensers, my object being to provide an operating means of simple, inexpensive construction whereby the movable parts of a plurality of tuning units may be connected for convenient collective and individual operation for the various purposes set forth in my prior applications serially numbered 683,756; 689,338; 10,293; 72,514; 10,833; 89,443; 91,197; 95,138; 98,558 and 108,074, and in my Patents 1,598,415; 15 1,598,441; 1,605,804 and 1,605,805.

My inventive idea is capable of embodiment in different mechanical structures, certain of which are shown in the accompanying drawings, but it is to be understood that 20 the structures shown are intended merely as disclosures of my invention in certain preferred forms and that its scope is as defined in the appended claims.

In the drawings, wherein like characters 25 of reference denote corresponding parts in the different views:—

Fig. 1 is a horizontal section through a plural tuning unit radio apparatus showing my improved operating mechanism in a preferred form embodied therein;

Fig. 2, a longitudinal section through the apparatus shown in Fig. 1 with the addition of a universal joint in the main shaft of my improved operating means;

Fig. 3, an end view of my mechanism;

Fig. 4, a transverse section on the line 4—4 of Fig. 1;

Fig. 5, a detail perspective view showing a preferred arrangement for yieldably supporting my improved operating mechanism;

Fig. 6, a detail perspective showing a preferred form of means for holding the laterally movable shaft of my operating mechanism in different laterally adjusted positions;

Fig. 7, a detail sectional view showing a slight modification of my operating mechanism;

Fig. 8, a detail sectional view showing another slight modification of my operating mechanism;

Fig. 9, a horizontal section through a plural tuning unit radio apparatus showing a structural arrangement different from the

preceding figures of the drawings, but embodying the same inventive idea as is disclosed in said preceding figures; and

Fig. 10, a front view of the mechanism shown in Fig. 9.

Referring to the drawings in detail, particularly to Figures 1 to 6, it will be observed that the tuning units, the movable parts of which are intended to be operated collectively or individually by my improved operating mechanism are indicated in this 60 instance as being in the form of variable plate condensers, each including, as usual, a set of stator plates *a* and a set of rotor plates *b*, the latter constituting the movable parts of said units. It is to be understood, 70 however, that the tuning units are illustrated herein as variable plate condensers merely for convenience, since they may be of any other form, such, for example, as coils, the only essential being that each of them 75 include a part movable to effect tuning thereof in order that my improved mechanism may be adapted to their operation.

In the preferred embodiment of my invention the tuning units are mounted in a row 80 in relative spaced relation with the axes of their rotor shafts 10 disposed in alinement with one another, but this is not essential as will appear by reference to Figures 9 and

10 of the drawings in which the rotor shafts 85 of the tuning units are disposed in parallelism. In any event, in carrying out my invention, the rotor shaft 10 of each tuning

unit is equipped with a gear wheel 12, and a plurality of pinions 14 are provided, one 90 for each tuning unit, arranged, respectively, in mesh with the gear wheels 12, said pinions being affixed to a shaft 16 with the result that

upon rotation of said shaft said pinions rotate their associated gear wheels 12 and 95 collective movement thus is imparted to the movable parts of the different tuning units. Shaft 16 may be in the form of a single

length of inherently resilient material as shown in Fig. 1, so that portions thereof may be flexed laterally without rotating to enable the individual pinions 14 by bodily 100 lateral movement to effect movement of the movable parts of their associated tuning

units individually, or, said shaft may be 105 composed of two or more sections connected together by one or more universal joints, as indicated at 18 in Fig. 2, to permit bodily

lateral movement of the individual pinions for effecting individual movement of the movable parts of the tuning units. In other words, each pinion 14 is rotatable and also 5 movable bodily laterally or in a direction at an angle to its axis of rotation and with respect to its associated gear wheel 12 to rotate said gear wheel, but due to the fixed connection of said pinions with shaft 16, rotation of 10 any pinion must necessarily result in collective rotation of all of them with consequent collective operation of the movable parts of all of the different tuning units, whereas, due to the flexibility of shaft 16, any given pinion 15 may be moved bodily laterally individually to effect movement of the movable part of its associated tuning unit individually, it being apparent that in any instance where three or more tuning units are connected together 20 for collective and individual operation by my mechanism, the frictional resistance of two or more is always present to prevent rotation of the shaft 16 whenever the latter is moved laterally to cause one of the pinions 25 to effect rotation of its associated gear wheel 12 individually.

The tuning units preferably are mounted upon the base 20 of a suitable cabinet which is inclusive of a front wall or panel 22 and 30 an end wall 24, the shaft 16 extending through an opening 26 in the end wall 24 whereby it may be equipped, exteriorly of the cabinet, with a suitable operating knob 28, opening 26 being elongated to permit lateral movement of the shaft, and a device 30 being provided to hold said shaft in any laterally moved position in which it may be placed, said device being secured to the end wall 24 and consisting preferably of a pair 40 of spring tongues 32, 32 between which the shaft extends and which frictionally grip the same, although any other suitable means may be employed in lieu of said device to accomplish the purpose thereof.

45 In the embodiments of my invention illustrated in Figures 1 and 2 it will be noted that the gear wheel 12 of the tuning unit nearest the end wall 24 of the cabinet is located exteriorly of the cabinet and has 50 formed integrally therewith a dial 34 having graduations thereon cooperating with a pointer 36 carried by said end wall for the convenience of the operator of the apparatus in determining the collectively operated positions of the movable parts of the respective 55 tuning units. Obviously, however, the dial and pointer are not essential and may be dispensed with, but whether a dial is or is not used it is equally manifest that the gear 60 wheel and pinion of the tuning unit nearest the end wall 24 of the cabinet may as readily be located within the cabinet as outside of the same.

The shaft 16 adjacent to each tuning unit 65 other than the one nearest the end wall 24

of the cabinet may be supported for rotation and lateral movement in any suitable manner, but I preferably employ the means shown consisting of a screw member 38 threaded in a bushing 40 secured to the front 70 wall or panel 22, said screw member extending through said panel and being equipped exteriorly of the casing with an operating knob 42 and at its inner end being in screw threaded engagement with a block 44 having 75 an opening or recess 46 in which the shaft 16 takes bearing. The portions of screw member 38 which engage the block 44 and bushing 40 are, respectively, provided with right and left hand screw threads as shown, 80 or with threads of different pitch, so that upon rotation of the screw member the block 44 may be moved inwardly or outwardly as desired with consequent lateral movement or flexure of the shaft 16 to produce the necessary bodily lateral movement of the adjacent pinion 14 for effecting individual movement of the movable part of its associated tuning unit. A leaf spring 48 secured at one end to the panel 22 bears at its 85 other end upon block 44 to maintain the adjacent pinion 14 in mesh with its associated gear wheel 12 and to prevent rotation of said block, to which end said spring preferably includes a pair of tongues 50 engaging opposite sides of the block 44.

Instead of screw devices for effecting lateral movement of different portions of the shaft 16, this result may be accomplished by a pivoted lever 52 as shown in Fig. 7, or 100 by a rod 54 slidable in a suitable bearing 56 and frictionally retained in different positions of adjustment by a leaf spring 58 as shown in Fig. 8, this latter arrangement being usable also in lieu of the device 30 as 105 is obvious.

From the foregoing it is apparent that the knob 28 and shaft 16 provides means for rotating the pinions 14 collectively to impart movement to the movable parts of the tuning 110 units collectively and that the screw members 38 with their associated movable parts provide means for moving portions of the shaft 16 laterally to produce bodily lateral movement of the pinions 14 individually to 115 effect movement of the movable parts of the tuning units individually, it thus being a relatively quick simple operation to first bring all of the tuning units substantially into tune with any selected wave length and then 120 to bring each unit individually into accurate tune with that wave length, all as set forth more fully in my aforesaid prior applications and patents.

To individually adjust the movable part 125 of the tuning unit located nearest to the end wall 24 of the cabinet the knob 28 simply is moved laterally, but if desired a screw member such as 38 or either of the structures shown in Figures 7 and 8 may be asso- 130

ciated with the shaft 16 adjacent to said tuning unit for individually operating the movable part thereof.

When any individual pinion 14 is moved bodily laterally its tendency to rotate about its associated gear wheel 12 instead of to rotate said gear wheel is prevented as aforesaid by the frictional resistance of the remaining units.

- 10 In Figures 9 and 10 of the drawings I have illustrated an arrangement which is essentially the same in mode of operation and result as the arrangement shown in Figures 1 and 2, the difference being that in Figures 9 and 10 the tuning units are arranged with the axes of the shafts of their movable parts in parallelism instead of alignment as in the preferred embodiment of my invention.
- 20 On the rotor shaft 10' each of the two tuning units included in the embodiment of my invention shown in Figures 9 and 10 is secured a gear wheel 12' and meshing with each gear wheel is a pinion 14'. Said pinions are secured respectively to a pair of shafts 16', 16' which are of suitable length and connected together for collective rotation by gear wheels 60. Each shaft extends through a slot in a panel 22' and one of them is equipped with a dial 34' and the other with a knob 62. They are supported adjacent to the gears 60 in suitable bearings 64 whereby they may be flexed to permit bodily lateral movement of the respective pinions 30 for individually operating the movable parts of their associated tuning units in the same manner set forth in connection with the preferred embodiment of my invention, and devices 30' are provided to hold them in any 40 laterally moved position in which they may be placed. By rotating either shaft the movable parts of the tuning units manifestly are caused to be moved collectively, and by 45 part of its associated tuning unit may be moved individually.

Form the foregoing description considered in connection with the accompanying drawings, it is believed that the construction, 50 operation and advantages of my improved operating mechanism will be fully understood. I desire to point out, however, that various modifications and additions other than those herein indicated may be made in 55 and to the structures shown within the spirit and scope of my invention as defined in the appended claims.

I claim:

1. In radio apparatus, a plurality of tuning units a part of each of which is movable, a plurality of members individual to the movable parts of said units and constantly in driving engagement therewith, said members being rotatable to move said movable parts and also being bodily movable

laterally to move said movable parts, and means rigidly connecting said members together as regards rotation and flexibly connecting them together as regards lateral movement whereby rotary movement of any member will cause the movable part of all of the units to be moved collectively and whereby said members may be moved laterally individually to move said movable parts individually.

2. In radio apparatus, a plurality of tuning units a part of each of which is movable, a driving member for the movable part of each unit constantly in driving engagement therewith, a shaft, each of said members being mounted rigidly on said shaft whereby they are rotatable collectively to move the movable parts of their associated tuning units collectively, said shaft being flexible whereby one of said members may be moved individually to move the movable part of its associated tuning unit individually.

3. In a radio apparatus, a plurality of tuning units a part of each of which is movable, a plurality of members individual to the movable parts of said units and constantly in driving engagement therewith, said members being rotatable to move said movable parts and at least one of them also being bodily movable laterally to move its associated movable part, and a shaft rigidly connecting said members together as regards rotation whereby rotary movement of any member will produce collective rotation of all the members with consequent collective movement of the movable parts of all of the tuning units, a portion at least of said shaft being flexible whereby at least one of said members may be moved laterally individually to move its associated movable part individually.

4. In radio apparatus, a plurality of tuning units a part of each of which is movable, a plurality of members individual to the movable parts of said units and constantly in driving engagement therewith, said members being rotatable to move said movable parts and at least one of them also being bodily movable laterally to move its associated movable part, a shaft rigidly connecting said members together as regards rotation whereby rotary movement of any member will produce collective rotation of all of the members with consequent collective movement of the movable parts of all of the tuning units, a portion at least of said shaft being flexible whereby at least one of said members may be moved laterally individually to move its associated movable part individually, and means for laterally moving said laterally movable member.

5. In radio apparatus, a plurality of tuning units a part of each of which is movable, a plurality of members individual to the

movable parts of said units and constantly in driving engagement therewith, said members being rotatable to move said movable parts and at least one of them also being 5 bodily movable laterally to move its associated movable part, a shaft rigidly connecting said members together as regards rotation whereby rotary movement of any member will produce collective rotation of all 10 of the members with consequent collective movement of the movable parts of all of the tuning units, a portion at least of said shaft being flexible whereby at least one of said members may be moved laterally individually to move its associated movable part individually, means for laterally moving said laterally movable member, and means for 15 holding said laterally movable member in any laterally moved position it may be 20 placed.

6. In radio apparatus, a plurality of tuning units a part of each of which is movable, a plurality of members individual to the movable parts of said units and constantly 25 in driving engagement therewith, said members being rotatable to move said movable parts and also being bodily movable laterally to move said movable parts, means rigidly connecting said members together as regards 30 rotation and flexibly connecting them together as regards lateral movement whereby rotary movement of any member will cause the movable parts of all of the units to be moved collectively and whereby said 35 members may be moved laterally individually to move said movable parts individually, and separate means for moving each of said members laterally individually.

7. In radio apparatus, a plurality of tun-

ing units a part of each of which is rotatable, said units being arranged in spaced relation with the axes of their rotatable parts in alinement, a spur gear fixed to the rotatable part of each unit, a shaft mounted parallel to the axes of the rotatable parts of said units, a plurality of pinions non-rotatably mounted on said shaft and disposed, respectively, in driving engagement with said gears, and means for rotating said shaft to cause said pinions to rotate the rotatable parts of said units collectively, a portion at least of said shaft being flexible whereby at least one of said pinions may be moved laterally individually to produce rotation of its associated spur gear individually. 45 50 55

8. In radio apparatus, a plurality of tuning units a part of each of which is rotatable, said units being arranged in spaced relation with the axes of their rotatable parts in alinement, a spur gear fixed to the rotatable part of each unit, a shaft mounted parallel to the axes of the rotatable parts of said units, a plurality of pinions non-rotatably mounted on said shaft and disposed, respectively, in driving engagement with said 60 gears, means for rotating said shaft to cause said pinions to rotate the rotatable parts of said units collectively, a portion at least of said shaft being flexible whereby at least one of said pinions may be moved laterally 65 70 individually to produce rotation of its associated spur gear individually, and means for laterally moving said laterally movable pinion.

In testimony whereof I hereunto affix my 75 signature.

DORSEY F. ASBURY
